ENVELOPE SEALING DEVICE

Filed June 10, 1930

Charles August Mezger
INVENTOR

UNITED STATES PATENT OFFICE

CHARLES A. MEZGER, OF BROOKLYN, NEW YORK

ENVELOPE SEALING DEVICE

Application filed June 10, 1930. Serial No. 460,146.

This invention relates to devices that are hand held for the operation of moistening and sealing the gummed flaps of envelopes, and has for its object to provide a neat and efficient implement whereby the moisture may be supplied for, and the flap sealed to the envelope by a single operation.

Another object of my improvement is to provide a sanitary means to apply the moisture for sealing an envelope and affixing a postage stamp to same.

Another object of my improvement is to provide a means to automatically apply the moisture to the surfaces for the purpose without the use of wicks or pads of absorbent material as heretofore used in the art.

A further object of my improvement is to provide a device for the purpose having a collapsible reservoir that may be filled with the moistening liquid by flexing the side walls of same.

I attain these results by means of a device of peculiar construction which is herewith described together with the operation of the same.

In the accompanying drawings forming part of this specification,

Fig. 1 is a side view of the device.

Fig. 2 is a front end view of the same.

Fig. 3 is a bottom view with the reservoir extended from the casing.

Fig. 4 is an enlarged longitudinal cross section of the device.

Fig. 5 is a top view of the moistening member.

Fig. 6 is a top view of the control or sealing member.

Fig. 7 is a side view of front end part and spring members.

Fig. 8 is a cross section of reservoir and springs on line 8—8 Fig. 7.

Fig. 9 is a longitudinal section of packing sleeve.

Fig. 10 is a section of same on line 10—10 Fig. 9.

Similar numerals refer to similar parts throughout the several views.

The casing 1, end piece 2, collapsible reservoir 3, inlet valve 4, moistening member 5, sealing member 6, packing 9, exhaust

valve 10, clamping plate 11, U spring 12, nut 17, flap closing member 19, oval head screw 37, and the tension regulator 38, constitute the various parts of the device, the casing 1, having the side apertures 14, the hole 16, flap closing member 19, bottom slot 23, and the threaded boss 36, being adapted to enclose the collapsible reservoir 3. The end piece 2 has a hole to admit the valve screw 10, an extended bottom portion having grooved sides 22 to engage with the edges of the slot 23 of the casing 1 and a nipple 21 to engage with the hole 20 in the reservoir 3, and is adapted to be attached to and close the opening in the front end 65 of the reservoir 3 and the casing 1.

The inlet valve 4 consists of a rubber bushing having a hinged flap and is fitted into a nipple having a grooved end to engage with a hole in the rear end of the reservoir 3 and has an extended threaded portion 15 adapted to pass through the hole 16 of the casing 1 and engage with the nut 17 to secure the valve 4 and the reservoir 3 to the casing 1.

The reservoir 3 is preferably formed of rubber with collapsible side walls and has a hole in the rear end to engage with the end groove of the inlet valve 4, a hole 20 to engage with the nipple 21 of part 2 and an opening in the front end the surrounding walls of which 18 are clamped between the clamping plate 11, the front plate of the U spring 12, and the end plate of part 2 by means of the valve screw 10 engaging 85 with the threaded hole of the clamping plate 11 so that the extended ends of the U spring 12 will contact with the outside of the walls of the reservoir 3, or the front plate of the U spring 12 may be clamped between the 90 wall 18 and the plate 11 so that the extended ends of the U spring 12 will contact with the inside of the walls of the reservoir 3 as shown in Fig. 8. The outside walls of the reservoir 3 may be plain or have raised panels 13 to register with the apertures 14 in the casing 1.

The moistening member 5 has a hollow portion 24 and a flat portion 26 extended from same; the hollow portion has a round- 100

ed end, beveled end and sides, a flat bottom, and a flat top 26 with a longitudinal groove 27 communicating by means of a small hole 28 with the hollow portion 24; an extended 5 nipple 25 communicating with the hollow portion 24 and adapted to engage with the nipple 21 of the part 2; the extended flat portion 26 has a hole 29 adapted to register with the threaded hole in the boss 36 of the 10 casing 1.

The sealing member 6 consists of a flat spring having the end of the portion 31 turned upwards, a hole 30 registering with the nipple 25 and a hole 33 registering with the hole 29, and is adapted to lie on top of the member 5 and be held in contact with same by the slotted regulator 38 sliding on the flat surfaces 26 and 32 to vary the tension of the contacting surfaces 26 and 31; 15 packing material may be attached to 31 to register with the hole 28 or a rubber packing sleeve 9 may be fitted over the portion 31 to contact with the surface 26 surrounding the groove 27 in member 5; but 20 when the surfaces of 26 and 31 are made so as to form proper contact the packing described will not be required.

The exhaust valve consists of a hollow screw 10 fitted with a rubber bushing 7 having one end contracted so that the edges 30 normally contact with each other but may be forced apart by the pressure of the air being forced out of the reservoir 3 when flexing the side walls of same.

When the reservoir 3 has been assembled as described with the end part 2, the nipple 21 and the inlet valve 4, the same may be inserted into the casing 1 as shown in Fig. 3, the stem of the inlet valve 15 being secured to the casing 1 by the nut 17 and the members 5 and 6 secured to the threaded boss 36 by the screw 37, the nipple 25 engaging with the nipple 21, thus connecting the member 5 to the reservoir 3 all as shown in Fig. 4.

The flap closing member 19 is hinged to the side of the casing 1 and is adapted to ride on the ungummed surface of the envelope flap and press the moistened gummed side of the same into sealed contact with the envelope by the tension of the spring 35.

A modified form of the device may be made of parts comprising a reservoir made of the casing 1 without the hole 16, the 55 apertures 14 and the slot 23, having the nipple 21 sealed to the casing 1 and the end of same sealed by a plain end piece 2 having an air vent and a filling port closed by a removable stopper, and the parts 5, 6, 9, 80 19, 36, 37, and 38 previously described and shown in the drawings.

The modified form of reservoir 1 is adapted to be filled through the port in the end piece 2 in the ordinary manner, the collapsible reservoir 3 being adapted to be

filled by submerging the inlet stem 15 in a liquid and flexing the side walls of the reservoir 3 through the apertures 14 of the casing 1 thereby expelling the air through the exhaust valve 10 and inducing the 70 liquid to enter through the inlet valve 4.

In the operation of the device the moistening member 5 being below the reservoirs 1 and 3, the moistening liquid will flow from the same by gravity through the nipples 21 and 25 into the hollow portion 24 of the member 5 and rise through the hole 28 into the groove 27 where the flow of the liquid is normally checked by the portion 31 of the movable sealing member 6 normally covering the outlet 27.

The portion of the envelope to be moistened is passed between the members 5 and 6 meanwhile being held in contact with the outlet 27 under tension of the portion 31 of member 6, the normal sealing contact being automatically restored when the moistened portion of the envelope is withdrawn from between the members 5 and 6.

To moisten and seal the gummed flap of an envelope by a single operation, lay the envelope flat with the ungummed side of the flap up, insert the flap between the members 5 and 6 with the closing member 19 contacting with the ungummed surface on top of the flap, and by moving the device along the flap the gummed surface of the same will be moistened by contact with the outlet 27 and pressed into sealed contact with the envelope by the closing member 19.

Postage stamps may be applied to envelopes in a sanitary manner by moistening a portion of the front of same with the device and by pressing the gummed postage stamps into position with the flat bottom of the member 5.

The casing 1, end piece 2, moistening member 5, sealing member 6, spring member 12, closing member 19, and the regulator 38 are preferably made of suitable metal press worked to the desired form, the front plate of the spring member 12 having a hole to admit the valve screw 10; the valve stem 4 the screw 37 and the valve screw 10 being a screw machine product.

The grooved outlet 27 referred to herein consisting of a channel forming a shallow basin in the member 5 to maintain a supply of moistening liquid and adapted to contact with and moisten a surface is the preferred form of moistening outlet for use with the device.

Other suitable forms of outlets controlled by a movable member adapted to automatically seal the same is broadly claimed to be within the scope of my invention.

Having described my invention, what I claim as new, and desire to secure by Letters Patent is —

1. A device for moistening and sealing envelopes comprising a casing enclosing a collapsible reservoir having inlet and exhaust valves, the reservoir adapted to be filled with a moistening liquid by alternately compressing and releasing the sides of same through apertures in the casing, a moistening member connected to and adapted to be supplied with liquid from the reservoir, the said member having a groove depressed in a surface of same forming a shallow basin for maintaining a supply of liquid from the reservoir, a control member having a tensional contact with the surface surrounding the grooved outlet adapted to form a normal seal for same, means for regulating the tension of the contacting surfaces, and a closing member adapted to press the moistened flap into sealed contact with the envelope.

2. A device for moistening and sealing envelopes comprising a collapsible reservoir adapted to be filled with a liquid by alternately compressing and releasing the walls of same, a moistening member connected to and supplied with liquid from the reservoir for moistening a portion of the envelope and the gummed flaps of same, a control member in movable contact with the moistening member adapted to normally form a seal for the outlet in same, and a closing member adapted to press the moistened gummed flaps into sealed contact with the envelope.

3. A device for moistening and sealing envelopes comprising a reservoir having inlet and outlet ports and walls adapted to be flexed to and fro whereby to charge the reservoir with a moistening liquid, an outlet from the reservoir adapted to engage with and moisten the flap of the envelope, a movable member adapted to contact the same with the outlet and form a normal seal for same, and a means for pressing the moistened gummed flap into sealed contact with the envelope.

4. A device for moistening and sealing envelopes comprising a reservoir having inlet and discharge ports and adapted to be charged with moistening liquid and discharge the same by means of an outlet adapted to engage with and moisten the gummed flap of an envelope or like surface, a movable member adapted to hold the surface in contact with the outlet and automatically seal the same when the surface is out of contact with the outlet, and a means for closing the moistened gummed flap and pressing the same into sealed contact with the envelope.

5. A moistening device comprising a member having a hollow portion adapted to be connected to a supply of moistening liquid and having an outlet adapted to engage with a surface whereby to moisten the

same, a movable member adapted to hold the surface in contact with the outlet and automatically seal the same by withdrawing the moistened surface from the outlet.
